(57) **CLAIM**

I claim the ornamental design for a handle for vacuum cleaner, as shown and described.

DESCRIPTION

FIG. 1 is a perspective view of a handle for vacuum cleaner showing my new design;

FIG. 2 is a right side view thereof;

FIG. 3 is a left side view thereof;

FIG. 4 is a front view thereof;

FIG. 5 is a rear side view thereof;

FIG. 6 is a top plan view thereof;

FIG. 7 is a bottom plan view thereof; and,

FIG. 8 is a perspective view thereof, the details shown in broken lines form no part of the claimed design.
